INTERLINING FABRIC FOR WEARING APPAREL**Georg Kufner, Munich, Germany**

Application June 23, 1953, Serial No. 363,454

1 Claim. (Cl. 139—420)

In tailoring it has been customary practice, especially as regards men's suits, to provide for a suitable stiffening or interlining material under the outer cloth. Such material consists of any one of a variety of stiffening fabrics, for example linen fabric or hair yarn fabric, the said fabrics being made with or without the use of horsehair. The said stiffening or interlining materials are employed in order to provide for a perfectly fitting garment.

Those interlining fabrics which contain wool or hair yarn are made both with and without a hairy surface or surfaces. Both types of fabrics have characteristic advantages and disadvantages. In the case of a fabric having a hairy surface the interlining made from such fabric will be found strongly to adhere to the outer cloth of the garment. At the same time, however, the surface roughness of the interlining material tends to rub against and thus damage the inner covering or lining of the garment under consideration. Moreover, there is a tendency for individual hairs of the stiffening material to penetrate the inner lining. It is for the reasons just mentioned that numerous tailor businesses have been refusing to use stiffening fabrics having hairy surfaces. However, the lining (serge or silk lining) is that part of a suit which is apt to wear out first, because it is comparatively thin. The useful life of the lining is reduced to a large extent if all movements of the outer cloth cause the lining to rub against a rough interlining fabric.

Besides stiffening fabrics of the above-mentioned type in which the under side and the upper side exhibit the same degree of roughness, there have been commercially introduced stiffening fabrics in which both sides show a smooth surface. Though it is admitted that these smooth-surface stiffening fabrics protect the inner lining of a suit or the like from premature wear, the fact has to be taken into consideration that such fabrics do not adhere to the outer cloth so strongly as is the case with rough fabrics.

Among the users of stiffening or interlining materials there exists a difference of opinion as to the relative merits of a strong adhesion between the interlining and the outer cloth brought about by the use of fabrics having the same degree of roughness on either side, and a lining-conservation effect brought about by using fabrics having smooth surfaces on either side. Thus, in order to meet all customer requirements, a large number of manufacturers of interlining materials have been keeping in stock both types of interlining fabric. This is a very uneconomical practice, especially when taking into consideration the fact that the keeping of stocks of ready-cut interlinings makes it necessary to have all sizes available in two different materials.

According to the present invention the above-mentioned disadvantages are eliminated by the provision of an interlining or stiffening fabric which is characterized in that the degree of roughness of its upper side differs from that of its under side. It is possible, also according to the invention, to produce these different degrees of roughness by providing either different degrees of

2

hairiness or different degrees of fuzziness. That surface of the fabric which has the lesser degree of roughness may also be made completely smooth.

Furthermore, also according to the invention, the lesser roughness or the smoothness, respectively, of one side of the fabric may be produced by subjecting one side of the fabric to a suitable treatment, for example to a shearing, singeing or pressing treatment. It is also possible, however, to produce the smoothness or lesser roughness or to increase the desired effect by using in the fabric a one-sided type of weave, such as a satin or twill weave. Still another method of practicing the invention resides in the manufacture of the stiffening fabric in the form of a double fabric of the plush or pile type and in cutting the fabric in a longitudinal direction.

Further objects and features of the invention will be apparent from the following description taken in conjunction with the accompanying drawing in which:

Figure 1 represents an embodiment of the invention in which a cloth weave is used;

Figure 2 represents an embodiment of the invention in which a satin weave is used; and

Figure 3 shows in combination an exaggerated cross section of a portion of a garment illustrating the stiff interlining interposed between an outer and inner lining making up the garment.

In the embodiment of Figure 1, the weft threads 1, 2, 3, 4 consist of goat's hair, the warp threads 5, 6 consisting of cotton. Because of the presence of a thick hairy fleece the upper side of the fabric is very rough. The roughness of this surface may still be enhanced by an additional roughening process performed, for example, by means of a machine similar to a carding machine. The under side 8 of the fabric is smooth, since here the hairs of the weft threads protrude only slightly beyond the warp threads. As has been mentioned earlier in this description, the said protruding hairs have been eliminated by a shearing, singeing or pressing operation. In order to remove the hairs from one side only of the fabric, the initial web of fabric having a uniform degree of hairiness on both sides is folded to form a double web, and the reverse side (now on the outside) is then singed or shorn. These different types of surface structures may also be attained by folding the initial web to form a double web, the out-turned reverse sides then being smoothed by a pressing operation.

In the embodiment of Figure 2, the weft threads indicated by the reference numeral 9 consist of rough yarn, whereas the warp threads indicated by the reference numeral 10 are smooth cotton threads. In this embodiment, the different degrees of roughness of the two sides of the fabric are largely brought about by the type of weave used. In order further to reduce the roughness of the smoother side of the material, the methods discussed in connection with the embodiment of Figure 1 may be employed.

The embodiment of Figure 3 shows an exaggerated cross-section of the stiff interlining comprising warp threads 12 and weft threads 14 interposed between inner lining 11 and outer cloth 13, the interlining being characterized by a relatively smooth side 12a and rough or hairy side 12b, the relatively smooth side being formed by a number of ways, for example, by shearing or singeing away the excess fleece or hair protruding from that side from weft threads 14. The rough side 12b shows the hairy portion of the weft threads protruding from the warp threads and into adhering contacts with outer cloth 13.

Stiffenings or interlinings for wearing apparel according to the invention may be manufactured in the form of webs or in the form of ready-cut pieces; in the latter

case they may be marketed in the form of ready-for-use stiffenings or interlinings.

I claim:

A wearing apparel comprising an outer cloth and a lining having interposed therebetween a stiff interlining, characterized in that the side of said stiff interlining adjacent the outer cloth is rough and is formed substantially of weft threads comprising a fleece of prickly hairy threads such as prickly goat hair, the prickles protruding only from the side of the interlining adjacent the outer cloth and in adhering contact therewith, the side adjacent the lining being smooth and comprising smooth warp threads such as cotton. 10
